UNITED STATES PATENT OFFICE

2,454,303

PORTABLE REFRIGERATOR

Morris Brodheim, Philadelphia, Pa.

Application December 4, 1945, Serial No. 632,693

2 Claims. (Cl. 62—31.)

1

This invention relates to portable ice refrigerators, and more particularly to a refrigerator adapted to be carried in the rear trunk compartment of an automobile.

A main object of the invention is to provide a novel and improved portable refrigerator which is very simple in structure, efficient in food storage arrangement, and readily accessible for placing food therein or removing food therefrom.

A further object of the invention is to provide an improved portable refrigerator adapted to be carried in the rear trunk compartment of an automobile, said refrigerator being internally arranged for very efficient utilization of cold air currents from its ice chamber for maintaining a low temperature in its food compartments.

Further objects and advantages of the invention will become apparent from the following description and claims, and from the accompanying drawings, wherein:

Figure 1 is a front elevational view of a portable refrigerator in accordance with the present invention.

Figure 2 is a rear elevational view of the refrigerator of Figure 1.

Figure 3 is a longitudinal vertical cross-sectional view of the refrigerator of Figure 1.

Figure 4 is a horizontal cross-sectional view taken on line 4—4 of Figure 3.

Figure 5 is a vertical transverse cross-sectional view of the refrigerator of Figure 1.

Figure 6 is a detail view of a portion of the door frame of the refrigerator of Figure 1 taken on line 6—6 of Figure 4.

Referring to the drawings, 11 designates the refrigerator housing which is generally rectangular in shape and is formed with a sloping upper longitudinal portion 12 adapted to provide clearance for the door of the rear trunk compartment of an automobile. The edge portions of the housing 11 are reinforced and protected against abrasion by metal guard strips 13 which may be chromium plated to improve the appearance of the unit. The walls of housing 11 are filled with suitable thermal insulating material such as pressed cork.

Provided centrally of the front wall 14 of housing 11 is a large door 15 hinged at 16, 16 to wall 14 and provided with a door latch 17. Door 15 is thermally insulated in the same manner as the housing walls. A metal door frame 18 is provided for receiving the door 15, and positioned in frame 18 adjacent hinges 16, 16 are a pair of switches 19 and 20 which are arranged to close their contacts responsive to the opening of door

2

15 but which are maintained in circuit-opening position when door 15 is closed. Positioned in the rear wall 21 of housing 11 are a pair of recessed male plug members 22 and 23. Mounted on the inner wall surface of sloping portion 12 are a pair of lamps 24 and 25, lamp 24 being a six-volt lamp and connected in circuit with switch 19 and plug member 22, and lamp 25 being a 110-volt lamp connected in circuit with switch 20 and plug member 23. When the refrigerator is used in the rear trunk compartment of an automobile, plug member 22 is connected to the automobile battery, whereby lamp 24 is energized when door 15 is opened. When the refrigerator is used in an apartment or other location where 110 volt lighting current is available, plug member 23 is connected to the 110 volt power supply, whereby lamp 25 will be energized when door 15 is opened.

20 The interior of housing 11 is divided into three compartments, there being a first ice compartment 26 at one end portion of the housing, a second ice compartment 27 at the other end of the housing, and a central food compartment 28. 25 Food compartment 28 is separated from ice compartment 26 by a metal partition 29 having an upper circulation vent 30 and a lower circulation vent 31. Food compartment 28 is operated from ice compartment 27 by a metal partition 32 having an upper circulation vent 33 and a lower circulation vent 34. Each ice compartment contains an ice tank 35 having a top thermally insulated closure 36, corrugated side walls 37, 37 and a corrugated bottom wall 38, said bottom wall 35 being spaced above a drain tray 39 by support lugs 40 carried by the bottom wall of ice tank 35. The upper portions of the side walls of each ice tank 35 are formed with air vents 41. Drain tray 39 is connected by a conduit 42 with a spigot 43 mounted on the outer surface of front wall 14. The top wall of housing 11 is provided with a closure 44 positioned above each ice tank 35 through which ice is placed in the ice tank.

40 45 Food compartment 28 contains a removable grating 45 defining a food shelf, said grating being about three quarters of the depth of the food compartment, thereby providing a space 46 at the forward portion of the food compartment for positioning tall articles such as bottles 48 therein. At the side portions of space 46 two spring clips 41, 41 are provided for engaging the necks of bottles 48 to maintain them upright in space 46, said spring clips being welded or otherwise rigidly secured to the respective vertical partitions 29 and 32.

A pair of handles 47, 47 are secured to the end walls of housing 11 to facilitate transportation of the refrigerator from one location to another.

It will be noted that door 15 is arranged so that when it is opened access is easily had to all parts of the food compartment 28. Bottles, such as milk bottles 48, 48, are secured at the side portions of compartment 28 by spring clips 41, 41 so that the rear portions of the compartment may be reached without removing the bottles. The spring clips 41, 41 are so arranged that they act as stop means preventing tray 45 from sliding forwardly on its supporting flanges during motion of the automobile, whereas tray 45 is formed with front, side and rear raised marginal abutment portions 49, preventing food from sliding off the tray.

While a specific embodiment of a portable refrigerator structure has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A portable ice refrigerator, comprising a substantially rectangular housing of heat insulating material, an upper longitudinal portion of said housing being inclined to define a sloping longitudinal surface, a first transverse partition wall positioned within said housing contiguous to and spaced from one end of the latter defining with the adjacent wall portions of the said housing a first ice compartment, a second transverse partition wall positioned within said housing contiguous to and spaced from the other end of the latter defining with the adjacent wall portions of said housing a second ice compartment, each partition wall having a circulating opening in its upper portion and another opening in its lower portion, said partition walls and the intermediate wall portions of said housing defining a food storage space between them, an ice receptacle positioned in each ice compartment, means for supporting each ice receptacle in substan-

tially spaced relation to the wall surfaces of its compartment, and a door for said food compartment, said door being located in a vertical longitudinal wall of the housing and being aligned with and substantially the same length as said food compartment.

2. A portable ice refrigerator, comprising a substantially rectangular housing of heat insulating material, an upper longitudinal portion of said housing being inclined to define a sloping longitudinal surface, a first transverse partition wall positioned within said housing contiguous to and spaced from one end of the latter defining with the adjacent wall portions of said housing a first ice compartment, a second transverse partition wall positioned within said housing contiguous to and spaced from the other end of the latter defining with the adjacent wall portions of said housing a second ice compartment, each partition wall having a circulating opening in its upper portion and another opening in its lower portion, said partition walls and the intermediate wall portions of said housing defining a food storage space between them, a door for said food compartment, said door being located in the longitudinal wall of the housing below said inclined longitudinal upper portion and being aligned with and substantially coextensive with said food compartment, a horizontal tray removably mounted in said food compartment, and bottle engaging means secured to each of said transverse partitions, said bottle engaging means being located forwardly of and in the same horizontal plane as said tray.
